UNITED STATES PATENT OFFICE.

MARSHALL TILDEN, OF LOS ANGELES, CALIFORNIA, ASSIGNOR OF ONE-HALF TO
GEORGE W. RANDALL, OF LOS ANGELES, CALIFORNIA.

HAND-STAMP.

1,069,356.

Specification of Letters Patent.

Patented Aug. 5, 1913.

Application filed April 25, 1912. Serial No. 693,193.

To all whom it may concern:

Be it known that I, MARSHALL TILDEN, a citizen of the United States, residing at Los Angeles, in the county of Los Angeles and State of California, have invented certain new and useful Improvements in Hand-Stamps; and I do hereby declare the following to be a full, clear, and exact description of the invention, such as will enable others skilled in the art to which it appertains to make and use the same.

This invention relates to improvements in hand stamps and more particularly to egg stamps and has for its object to provide a stamp which will be so constructed and arranged that a name or other desired inscription may be printed upon an egg, thereby disclosing the name or identity of the egg and date of its production; thus preventing deception in the sale of inferior eggs to the consumer.

A further object of my invention is to provide a stamp for use not only on convex surfaces but on concave and flat surfaces as well.

Briefly stated this invention is a combination stamp telescopic in construction, or a stamp within a stamp, removably secured or locked one within the other and operated by the handle of the inner stamp the same way as is customary with any ordinary stamp.

Other objects and advantages will be apparent from the following description and more particularly pointed out in the claims.

In the drawings Figures 1 and 2 are side elevations of the invention. Figs. 3 and 4 are side elevations partly in section. Fig. 5 is a bottom plan. Fig. 6 is a side elevation partly in section of the outer stamp. Fig. 7 is a side elevation of the inner stamp. Fig. 8 is a sectional view of a convex disk. Fig. 9 is a top plan and sectional elevation of a modified form of the rubber diaphragm. Fig. 10 is a top plan and an edge view of a diaphragm. Fig. 11 is a perspective view of type. Fig. 12 is a perspective view of a rubber cushion type-holder.

Referring to the drawings, 1 represents the inner stamp which also serves as a handle for the proper manipulation of both the inner and the outer stamp which, combined, form the stamp.

2 represents the outer stamp which is removably secured to the inner stamp by the screw 3 through slot 4. The type 5 is se-

cured to diaphragm 6 which is drawn over the lower end of the outer stamp 2 and secured by band 7 as shown in Figs. 1 and 2.

The spring 8 encircles the inner stamp, its ends engaging shoulders on the inner and outer stamp, as shown in Figs. 3 and 4. The spring is of such strength that the impression of the outer stamp is made before the type of the inner stamp reaches the surface to be printed as the force of the spring must be overcome before the inner stamp can reach said surface; thus obviating the making of a blurred impression. It is possible to operate the stamp without the use of the spring but its use is preferred.

9 is a mortised rubber cushion or type holder secured to the bottom of the inner stamp, as shown in Figs. 3 and 4.

10 is a perforated type for use in type-holder. The perforation renders the type more flexible and allows it to conform to the surface to be printed. Ordinary type may be used if desired.

In adjusting the rubber diaphragm 6 to the outer stamp 2, it is placed over the grooved end 11 as shown in Fig. 6, with the opening directly over the center. The metal band 7 is then placed over the end of the rubber diaphragm pressing its edges over the groove. Said edges are then trimmed so that when the band is pressed farther into position the ruffled edges of the rubber fall into the groove, thus fastening the diaphragm securely. The diaphragm is formed of thin rubber, consequently it is very flexible and yielding and in conjunction with the mortised rubber cushion on the inner stamp will conform to any surface either flat, convex or concave.

It will be seen and understood that, in operation, the telescopic construction, or the sliding of one stamp within the other, which is controlled by the spring, allows the type at the end of each stamp to meet the inking surface of an ordinary inking pad for inking purposes when applied in the manner usual with hand stamps. When removed from the pad the spring forces the stamps to take the position shown in Figs. 2 and 3 and it is then ready to make an impression upon an egg or other surface, as shown in Fig. 4.

By the same operation as above described an impression may be made upon a flat surface, but preferably the outer stamp should be locked to the inner stamp, as shown in

Fig. 1, thus preventing the telescopic action and forming an ordinary hand stamp. For printing on concave surfaces the end of the inner stamp Fig. 7 may be made convex or 5 the disk, flat on one side and convex on the other, as shown in Fig. 8, may be inserted between the rubber cushion and the end of said inner stamp and accomplish the same purpose. Preferably the same result may 10 be obtained with no readjustment of the stamp, as stated above. The construction of this stamp is such that, at the will of the operator, he may make an impression with both inner and outer stamp or with the outer 15 stamp only. Thus if it is not desired to date certain eggs the date may be omitted without removing the dating type by simply holding the outer stamp between the thumb and finger when operating it.

20 What is claimed is:—

1. A hand stamp telescopic in construction, comprising a stamp within a stamp movably secured one within the other; a rubber cushion secured to the lower end of the 25 inner stamp and a rubber diaphragm having a central opening secured to the lower end of the outer stamp said hand stamp automatically adjusting itself for inking and printing purposes as shown and described.

30 2. A hand stamp telescopic in construction comprising a stamp within a stamp, movably secured one within the other; a type-bearing mortised rubber cushion secured to the lower end of the inner stamp and a type-bearing 35 rubber diaphragm having a central opening secured to the lower end of the outer stamp: said hand stamp automatically adjusting itself for inking purposes and for printing upon either convex, concave or flat 40 surfaces.

3. A hand stamp telescopic in construction comprising an inner and an outer type-bearing portion, movably secured one within the other; a mortised rubber cushion secured to the lower end of the inner portion 45 and a rubber type-bearing diaphragm secured to the lower end of the outer portion: said stamp automatically adjusting itself for inking and printing purposes.

50 4. A combination hand stamp telescopic in construction, comprising two type bear-

ing portions one partially enveloping the other, a rubber cushion secured to the lower end of the inner portion and a rubber diaphragm secured to the lower end of the outer portion, a screw 3 movably securing said portions and an adjusting spring 8 encircling the inner type-bearing portion, the ends of said spring engaging both said portions: said stamp being adapted to print 60 either with the outer portion or with both combined without readjustment.

5. A combination hand stamp telescopic in construction, comprising two type bearing portions movably secured one within the other, the inner of said portions being provided with a mortised rubber cushion; the outer portion having a typebearing rubber diaphragm with a central opening, secured 70 to its base.

6. A hand stamp comprising a tubular base member having a perforated elastic type-bearing diaphragm secured to the lower end thereof; an inner member having an elastic cushion mounted upon the lower end 75 thereof slidably mounted in said base member, said cushion having an opening therein adapted to be brought into register with the perforation in the diaphragm; means to retain said members in their operative position; and means to immovably lock said members together when desired.

7. A hand stamp comprising a tubular base member having a rubber diaphragm secured to the lower end thereof; an inner 85 member having a rubber cushion mounted upon the lower end thereof slidably mounted in said base member, said cushion being adapted to bear upon the inner surface of said diaphragm when in an operative position; means to retain said members in their 90 operative position; and rubber type adapted to said members for inking and printing purposes, all substantially as shown, described and for the purposes set forth.

95 In testimony whereof I affix my signature, in presence of two witnesses.

MARSHALL TILDEN.
